UNITED STATES PATENT OFFICE

146,005

DESIGN FOR A MARBLE GAME ENCLOSURE

Frederick H. King, Detroit, Mich.

Application October 29, 1945, Serial No. 123,287

Term of patent 14 years

(Cl. D34—5)

To all whom it may concern:

Be it known that I, Frederick H. King, a citizen of the United States, residing at Detroit, in the county of Wayne and State of Michigan, have invented a new, original, and ornamental Design for a Marble Game Enclosure, of which the following is a specification, reference being had to the accompanying drawings, forming part thereof, wherein:

Fig. 1 is a top plan view of a marble game enclosure showing my new design.

Fig. 2 is a side view of such enclosure.

Fig. 3 is a front view of the same.

Fig. 4 is a fragmentary rear view.

Fig. 5 is a perspective view of the marble game enclosure shown in Fig. 1.

I claim:

The ornamental design for a marble game enclosure, as shown.

FREDERICK H. KING.
